UNITED STATES PATENT OFFICE

ROBERT E. MOORE, OF ST. LOUIS COUNTY, MISSOURI.

COMBINED CAR DOOR AND PARTITION.

1,085,753.

Specification of Letters Patent.

Patented Feb. 3, 1914.

Application filed May 26, 1913. Serial No. 770,017.

To all whom it may concern:

Be it known that I, ROBERT E. MOORE, a citizen of the United States, and resident of St. Louis county, Missouri, have invented 5 certain new and useful Improvements in Combined Car Doors and Partitions, of which the following is a specification containing a full, clear, and exact description, reference being had to the accompanying 10 drawings, forming a part hereof.

My invention relates to improvements in combined car doors and partitions, and the object of my invention is to construct an inner car door of such dimensions as to be 15 employed either as a door or a cross partition, and to provide an overhead carrying means for the door and also to arrange a simple means for locking the door in either position.

20 With the above purposes in view my invention consists in certain novel features of construction and arrangement of parts as will be hereinafter described, pointed out in the claims and illustrated by the accompanying drawings, in which—

Figure 1 is a simple section of a grain car equipped with a door constructed according to my invention; Fig. 2 is an enlarged transverse sectional elevation of a car showing 30 my improved door employed as a cross partition; Fig. 3 is a sectional plan of a fragment of a car showing two of my improved doors employed as inner car doors; and Fig. 4 is a fragmental inside elevation showing 35 the means for holding the door when employed as an inner car door.

An ordinary grain or box car is usually provided with two side door openings and I contemplate employing two inner doors of 40 identical construction, hence I will limit my description to a single door.

In the drawings the numeral 5 designates 45 an overhead track which extends from a point midway over the car door opening to the end of the car and is hung intermediate its ends by the hangers 6 which are preferably secured to the ridge pole of the car. Arranged for travel on the track 5 is a 50 bar 8 the body of which is preferably non-circular. The upper end of the bar is reduced and threaded and the threaded end is inserted through the opening in the lower end of the trolley 7, and a nut 9 secures the

bar to the trolley in such manner as to permit of the bar turning relative to the trolley. 55

The numeral 10 designates the combined inner door and partition which is constructed identically like the common inner grain door, except for width it being necessary that 60 the door be as wide as the car. Secured to the door is a vertically arranged channel-iron 11 which embraces the lower end of the noncircular bar 8. Carried by the bar, above the channel-iron 11, is a slide-bolt 12 65 and secured to the bar 8 is a pair of pins 13, the lowermost one of which provides means in conjunction with the slide-bolt 12 for holding the door against vertical movement and the uppermost pin 13 provides means in 70 conjunction with the slide-bolt 12 for holding the door in an elevated position for carrying from one point to another in the car.

Adjacent each corner of the door 10 there is a bar 14, each of which projects beyond 75 the side margins of the door. Secured to the inside faces of the sides of the car are the notched rails 15 and 16, which in conjunction with the bars 14 provide means for holding the door as a partition at any desired point lengthwise of the car. The ends of each of the rails 15 and 16 next adjacent the door openings are bent to form hooks 17 80 which in conjunction with the bars 14 provide means for holding the car door, when 85 employed as an inner door, in place.

It will be observed that by the provision of an inner car door of a width equal to the width of a car (inside dimensions) the same door may be employed either as a door or a 90 cross partition, and by the provision of the notched rails 15 and 16 the hooks 17 on the rails and the bars 14 carried by the doors, the door and car are provided with door-securing means, so as to eliminate all nailing. 95

By the arrangement of the trolley and overhead track a very simple means is provided for the carrying of the door from one position to another, so that a single operator may accomplish this act. 100

I claim:

1. In combination with a car, a door, and coöperating securing devices carried by the car and the door for holding the door in position over a door opening or crosswise of 105 the car to be employed as a partition.

2. In combination with a car, a door, coöperating securing devices carried by the

car and the door for holding the door in position over a door opening or crosswise of the car to be employed as a partition, an overhead track secured in the car, and a 5 trolley device secured to the door for carrying the door to different points within the car.

3. In combination with a car, an overhead track within the car and a pair of notched rails secured within the car, a door, a trolley arranged for travel on the overhead track, a

bar having a swivel connection with the trolley, and means for vertically adjustably securing the door to the bar.

In testimony whereof, I have signed my 15 name to this specification, in presence of two subscribing witnesses.

ROBERT E. MOORE.
